(57) **CLAIM**

The ornamental design for a water fitness equipment, as shown and described.

DESCRIPTION

FIG. 1 is a perspective view of the top, side and front of a water fitness equipment of my new design;

FIG. 2 is a side elevational view thereof;

FIG. 3 is a front elevational view thereof;

FIG. 4 is a rear elevational view thereof;

FIG. 5 is a top elevational view thereof;

FIG. 6 is a bottom elevational view thereof; and,

FIG. 7 is a side elevational view thereof.

The broken lines shown in the figures are included for the purpose of illustrating portions of the water fitness equipment and form no part of the claimed design.

1 Claim, 5 Drawing Sheets
